UNITED STATES PATENT OFFICE.

JOSEPH A. GABRIEL, OF CLEVELAND, OHIO.

BELL-OPERATING MECHANISM.

Application filed June 9, 1926. Serial No. 114,870.

This invention relates to bell operating mechanism for blast furnace charging bells and the like, and has for its object the provision of a novel form of mechanism of this class in which a minimum of power is required to operate the bell.

Another object is to provide a mechanism of this class in which the operating cable slack and stretch will be automatically taken up.

A further object is to provide a mechanism of the class described in which breakage of the operating cable due to excessive overload is prevented.

A still further object is to provide a bell operating mechanism having the novel construction, design and combination of parts hereinafter described and illustrated in the accompanying drawings.

20 In the drawings—

Figure 1 is a diagrammatic side elevation showing my invention applied to the charging bell of a blast furnace.

Figure 2 is a plan thereof.

25 Figure 3 is an enlarged side elevation of the bell operating machine.

Figure 4 is a sectional view through the bell operating machine.

Figure 5 is a rear elevation of the same.

30 Figures 6, 7, 8, 9 and 10 are diagrammatic views of various modified applications or embodiments of my invention.

Referring more particularly to the drawings, the numeral 2 designates the charging bell of a blast furnace which is of standard construction, and 3 designates the lower end of the hopper portion of the furnace. The lower edge of the hopper forms a seat 4 against which the bell is seated when closed.

40 The valve or bell is operated by a rocking beam or lever 5, fulcrumed in the customary way at 6 upon a support 7 extending upwardly from the furnace superstructure (not shown). A connecting rod or link 8 is connected to the forward end of the lever 5 to the bell 2, and a counterweight 9 is mounted adjacent the rear end of the lever 5. The counterweight 9 is of a weight capable of balancing approximately ninety per cent of the weight of the bell and rod or link.

50 The bell operating machine is designated as a whole by the letter A, and comprises a housing or base 12 on which is supported a motor 13. The armature shaft of the motor 13 carries a pinion 14 which is in mesh with a gear 15 on a shaft 16 which is cou-

pled at 17 to a worm-gear shaft 18. The shaft 18 carries a worm-gear of usual construction which is meshed with a worm-wheel of usual construction carried by a 60 shaft 19 journaled in bearings 20 and 21, the worm and worm-wheel casing 22.

The shaft 19 carries a pinion 23 which is in mesh with a gear 24 mounted on a stub shaft 25. A crank arm 26 is journaled on a 65 stub shaft 27 in line with the shaft 25. A crank pin 26^a is mounted in a bearing in the lower end of the crank arm 26 and in a bearing 28 in the gear 24.

An operating lever 29 is pivotally 70 mounted at its rear end on a shaft 30 mounted in bearings 31 and 32 and is connected intermediate its ends to the crank pin 26^a by connecting links 33 which are journaled on the pin 26^a and on a pin 34 75 passing through a suitable bearing aperture in the lever 29.

The free or lower end of the lever 29 is provided with a bearing aperture in which is mounted a pin or shaft 35 carrying 80 counterweights 36.

The counterweights 36 are connected by a yoke 37 which is provided with an eye 38 to which one end of the bell operating cable 39 is secured while the other end is secured 85 to the rear or counterweighted end of the lever or beam 5.

In operation the crank operated links 33 move the lever 29 and counterweights 36 up or down to open or close the bell 2. The beam 5 being counterweighted to within ten per cent of the load, the ten per cent of unbalanced bell and rod weight is all that is required to be moved at first until the bell begins to seat. As the bell seats the load 95 is increased and the counterweights 36 are raised out of their normal or inactive vertical position. As the counterweights 36 move out of their vertical position they throw their weight into action and aid in 100 closing the bell 2.

Due to the novel construction of this apparatus the crank goes to dead center as the lever 29 reaches its end of travel, and the machine A may, therefore, be run in a complete circle without breakage.

105 It will also be noted that the counterweights 36 serve to automatically take up slack in the operating cable 39, and also serve as a safety means to prevent breakage 110 of the cable if a piece of scrap should be caught between the bell 2 and its seat or

some other means prevent the normal seating of the bell.

In Figures 6, 7, 8, and 9 I have shown in diagrammatic form, various modified embodiments of my invention, all of which embody a shiftable or rocking counterweight, adapted to cushion the application of power to the bell operating lever, to take up the slack in the cable, and to serve as a safety means to prevent breakage of the cable if a piece of scrap should be caught between the bell 2 and its seat.

In the construction of Figure 6, the bell operating lever 5 is provided with a pivotally mounted crank-shaped counterweight 9^a to which one end of the actuating cable 39 is secured while the other end of the cable is secured to a power operated crank arm 45, the cable being trained over an elevated sheave so as to cause an upward pull on the counterweight to thereby rock said counterweight when power is applied to the cable, and thus cushion the application of power from said cable to said bell.

In the construction of Figure 7, the bell operating lever 5 is connected by the cable 39 to one arm of a crank-shaped counterweight 46 which is pivotally mounted at its crank portion on a vertically reciprocating rack 47 of a power actuating means 48. The counterweight 46 will thus be shifted or rocked about its pivotal mounting when power is transmitted from said rack 47 to said cable 39 and lever 5.

In the construction of Figure 8, the bell operating lever 5 is connected by the cable 39 to one arm of a crank-shaped counterweight 49 which is pivotally secured at its crank to a crank pin 50 of a suitable power mechanism 51.

In Figure 9 a carriage 52 is shown mounted for movement on a track 53 and carrying a counterweight 54 pivoted intermediate its ends to the carriage, and an actuated cable 55 is secured to the upper end of the counterweight while an actuating cable 56 is secured to the carriage, whereby when power is applied to the cable 56 the counterweight will be rocked about its pivotal connection to cushion the application of power to the actuated cable 55.

In Figure 10 I have shown a modification similar to that shown in Figure 6 except that the cable 39 is passed directly to the power operated crank arm 45 and the elevated sheave is omitted.

In each of the several embodiments of my invention the mechanism on one side of the pivoted counterweight constitutes an actuating means while the mechanism on the other side constitutes the actuated means, and such actuating and actuated means are secured, respectively, to spaced points on the counterweight, the portion of the counterweight between said spaced points constituting and

acting as a lever arm for initially swinging said counterweight about one of said spaced points as an axis and for thereafter effecting movement of the actuated means.

While I have shown and described certain specific embodiments of my invention, it will be understood that I do not wish to be limited thereto, since various other modifications may be made without departing from the scope of my invention as defined in the appended claims.

I claim:

1. A bell hoisting mechanism for blast furnace bells comprising the combination with a blast furnace bell, of a rocking lever, a rod connecting the forward end of said lever with said bell, said lever having its rear end counterweighted to balance the major portion of the weight of said bell and rod, and means for rocking said lever to close said bell, said means comprising an operating lever pivoted at one end to a fixed frame, a counterweight pivoted to the other end of said lever, a connecting element connecting said counterweight and the rear end of said rocking lever, and means for rocking said operating lever about its pivot.

2. A bell hoisting mechanism for blast furnace bells comprising the combination with a blast furnace bell, of a rocking lever, a rod connecting the forward end of said lever with said bell, said lever having its rear end counterweighted to balance the major portion of the weight of said bell and rod, and means for rocking said lever to close said bell, said means comprising an operating lever pivoted at one end to a fixed frame, a counterweight pivoted to the other end of said lever, a connecting element connecting said counterweight and the rear end of said rocking lever, and means for rocking said operating lever about its pivot, said means including a crank, a link connecting said crank and said lever, and means for operating said crank.

3. A bell hoisting mechanism for blast furnace bells comprising the combination with a blast furnace bell, of a rocking lever, a rod connecting the forward end of said lever with said bell, said lever having its rear end counterweighted to balance the major portion of the weight of said bell and rod, and means for rocking said lever to close said bell, said means comprising an operating lever pivoted at one end to a fixed frame, a counterweight pivoted to the other end of said lever, said counterweight being of greater weight than the uncounterbalanced weight of said bell and rod, a cable connecting said counterweight and the rear end of said rocking lever, and means for rocking said operating lever about its pivot.

4. A bell hoisting mechanism for blast furnace bells comprising the combination with a blast furnace bell, of a rocking lever,

a rod connecting the forward end of said lever with said bell, said lever having its rear end counterweighted to balance the major portion of the weight of said bell and rod, 5 and means for rocking said lever to close said bell, said means comprising an operating lever pivoted at one end to a fixed frame, a counterweight pivoted to the other end of said lever, said counterweight being of greater weight than the uncounterbalanced weight 10 of said bell and rod, a cable connecting said counterweight and the rear end of said rocking lever, and means for rocking said operating lever about its pivot, said means including a motor, a crank operated by said motor and a link connecting said crank and 15 said lever.

5. A bell hoisting mechanism for blast

furnace bells comprising the combination with a blast furnace bell, of a rocking lever 20 having its forward end connected to said bell by a rod and having its rear end counterweighted to balance the major portion of the weight of said bell and rod, an operating 25 lever pivoted at one end to a fixed frame, a counter-weight pivotally secured to the other end of said operating lever and connected to said rocking lever, said last named counter-weight being adapted to balance the uncounterbalanced weight of said bell and rod, 30 and means for rocking said operating lever about its pivot.

In testimony whereof, I have hereunto signed my name.

JOSEPH A. GABRIEL.
